UNITED STATES PATENT OFFICE.

VITO NUNZIO ROSATO, OF YONKERS, NEW YORK.

AEROPLANE.

1,116,926.

Specification of Letters Patent.

Patented Nov. 10, 1914.

Application filed August 18, 1913. Serial No. 785,262.

To all whom it may concern:

Be it known that I, VITO NUNZIO ROSATO, a citizen of the United States, and a resident of Yonkers, in the county of Westchester and State of New York, have invented a new and Improved Aeroplane, of which the following is a full, clear, and exact description.

This invention relates to aeroplanes and 10 has particular reference to the construction thereof with respect to increasing stability and safety.

More specifically stated, I provide an aeroplane body having longitudinally arranged passageways for air, and such passageways are controlled by certain pivoted doors or shutters for the purpose of increasing the safety of the device in case of accident.

20 A further object of the invention is to provide an upwardly inclined passageway through the aeroplane body and mount therein a wheel having geared connections with an auxiliary propeller for the purpose 25 of steadyng the machine in ordinary flight.

The foregoing and other objects of the invention will hereinafter be more fully described and claimed and illustrated in the drawings forming a part of this specification 30 in which like characters of reference indicate corresponding parts in all the views, and in which—

Figure 1 is a plan view, partly broken away, of a preferred form of this invention; 35 Fig. 2 is a side elevation of the same; Fig. 3 is a longitudinal section on the line 3—3 of Fig. 1; Fig. 4 is a diagram indicating the movable controlling devices. Fig. 5 is a front elevation of the machine; and Fig. 6 40 is a perspective view of the front axle construction.

The several parts of the device may be made of any suitable materials, and the relative sizes and proportions of the same may 45 be modified to a considerable extent without departing from the spirit of the invention hereinafter more fully set forth and specifically claimed.

As shown, the machine is preferably of 50 the biplane type comprising the two main planes 10 and 11 extending transversely and one above the other, as is usual in machines of this type. I also provide auxiliary planes 55 12 and 13 which are smaller than the main planes and are arranged at the rear end of the machine. I also provide stabilizing

planes 14 which extend from the main to the auxiliary planes and preferably parallel to the longitudinal axis of the machine.

The body 15 of the device is somewhat in 60 the nature of a boat, having its front end tapered as shown at 15'. The main plane 10 extends laterally from the body 15 in both directions. The body 15 is provided with an opening 16 between the two planes 10 and 11 65 and there is a current of air directed through said opening between the planes under ordinary conditions. The passageway for this current of air is restricted on the sides by means of walls 17 and 18 connecting the main planes aforesaid. The body 15 is provided also with an opening 19 in its bottom which communicates with an inclined upwardly directed wind passageway 20 bounded on the rear by a wall 21 75 and on its sides by walls 22 and 23.

At the rear portion of the machine there is provided an auxiliary wind passageway 24 bounded on the bottom and top by the planes 12 and 13 respectively, and on its sides by 80 the walls 25 and 26. The front wind passageway is adapted to be more or less closed by operation of a shutter 27 mounted on a horizontal pivot 28 and controlled by means of flexible connections 29 leading to a hand lever 30 within convenient reach of the aviator on the seat 31. The current of wind leading to the passageway 20 is controlled in its direction and course by means of a wall 32 constituting a part of the body 15. Said 85 current of air is guided also by a fixed wall 36 extending across the front portion of the passageway 20. A wheel 37 is journaled on a transverse pivot within said passageway 20 and is adapted to be driven by the current 90 of air passing through the passageway 20, as indicated in Fig. 3.

The main propelling devices include a motor 38 having connections by suitable shafts and gearing to a set of three propellers 39 and 40. The propeller 39 is mounted at the point or nose of the machine, and the other two are located on either side of the body 15 and in front of the main planes. The wheel 37, as indicated, serves 105 as an auxiliary propelling means and has suitable gearing shown at 41 leading to an auxiliary propeller 42 just in front of the auxiliary planes 12 and 13. The primary purpose of this propeller 42 is to steady the 110 machine in its flight. The current of air passing through the passageway 24 is con-

trolled by a shutter 43 pivoted on a horizontal axis 44 adjacent the rear portions of the planes 12 and 13. This shutter has flexible connections 45 leading forwardly to a hand lever 46.

At the front of the aeroplane I provide horizontal stabilizing planes 47 and 48 controlled by hand levers 47' and 48' respectively. A rudder 49 is pivoted on a vertical axis 50 in the rear of the machine and is controlled by flexible connections 51 leading forwardly to a foot lever 52. The rudder is made of peculiar form, being substantially wedge-shaped and is comparatively wide at its rear end, as shown in Figs. 1 and 4. The rudder as well as the other main portions of the device will be made hollow and as light as possible in proportion to the required strength.

20 Supporting wheels 53 and 54 are provided on front and rear axles 53' and 54' respectively, and these wheels and axles are supported by means of yokes 55 having suitable connection with a hand lever 56 whereby said yokes 25 and wheels may be thrown upwardly toward the body 15 so as to bring the wheels on opposite sides thereof. Each pair of wheels is permitted to occupy the position indicated by virtue of an arched formation of the 30 axle to which the wheels are connected.

The operation of the device may be briefly described as follows: The wheels 53 and 54 support the machine while it is on the ground and assist the starting thereof in the usual way. After the machine leaves the ground, the wheels are preferably elevated as above referred to. The main and auxiliary propellers cause the main and auxiliary planes to lift the machine and the 40 stabilizing and steering devices are operated for their several purposes. The machine, if descending, while in normal horizontal position, will receive an air current through the opening 19 which acted upon the wheel 19 45 and finally upon the auxiliary propeller 42, will have a tendency to make the machine glide and hence increase the safety of the machine. It will be noted, furthermore, that when the shutters 27 and 43 are closed, they 50 will act in the nature of a brake or means to retard the speed of the machine while gliding through the air. They also act to direct the machine upwardly or downwardly.

The body 15 being somewhat boat-shaped 55 is well adapted to be supported upon the surface of a body of water. At such time a shutter 33 may be operated by connections 34 and a lever 35 to quickly close the opening 19, keeping the water out of the passage- 60 way 20.

Having thus described my invention, I

claim as new and desire to secure by Letters Patent:—

1. In an aeroplane, the combination of a central longitudinal substantially boat-shaped body, a main plane extending laterally on each side of said body, another main plane above the first mentioned plane and vertical partitions providing a longitudinal central air space, propelling and steering means for the machine, a portion of the propelling means including a power wheel acted upon by a current of air passing through said air space, means to control the current of air therethrough, an auxiliary plane in the rear of and parallel to the main plane, and stabilizing planes 14 on opposite sides of the body extending between the main and auxiliary planes and providing a large central vertical substantially rectangular air space.

2. In an aeroplane, the combination of a central longitudinally arranged boat-shaped body having an opening through its bottom substantially at the center, propelling and steering means, a vertically extending passageway leading upwardly and rearwardly from said opening, power means journaled in said passageway, an auxiliary propeller connected to said power means, and means to control the currents of air to and through said passageway.

3. In an aeroplane, the combination of a longitudinally arranged boat-like body having a central opening through its bottom, main propelling and steering devices, an air passageway extending upwardly and rearwardly from said opening, means to control the passage of air through said passageway, a power wheel journaled on a horizontal axis in said passageway substantially closing the same, an auxiliary propeller, and gearing extending between said wheel and said auxiliary propeller.

4. In an aeroplane, the combination of lifting planes, stabilizing planes arranged in fixed position in longitudinal parallel relation and connected with said lifting planes, a pair of movable stabilizing planes at the front of the machine, a vertically arranged rudder at the rear end of the machine, said rudder being substantially wedge-shaped, and a series of independent levers within reach of the aviator for the control of said movable operating devices.

In testimony whereof I have signed my name to this specification in the presence of two subscribing witnesses.

VITO NUNZIO ROSATO.
